(57) **CLAIM**

The ornamental design for an enclosure for electronic components, as shown and described.

DESCRIPTION

FIG. 1 is an elevated perspective view of an enclosure for electronic components incorporating a design according to the invention.

FIG. 2 is a left side view of the enclosure of FIG. 1.

FIG. 3 is a right side view of the enclosure of FIG. 1.

FIG. 4 is an end view of the enclosure of FIG. 1; and,
FIG. 5 is a bottom view of the enclosure of FIG. 1.
